UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

UNCOUPLING DEVICE FOR RAILWAY-CAR COUPLERS.

Application filed November 12, 1926 Serial No. 147,986.

The device relates to what is known in the art as a push-down or vertical plane type of uncoupling device for railway cars and comprises a one or two-piece operating lever attached to the coupler in the usual manner and pivotally connected to a suspension link which is pivotally connected to a fulcrum mounted upon the car. Such an arrangement provides a flexible construction and, furthermore, allows the coupler lock pin to raise in a vertical line when lifted by the uncoupling device.

In the drawings:

Fig. 1 shows an application of the device to a railway car.

Fig. 2 shows an enlarged elevation of the fulcrum and associated parts of the device.

Fig. 3 is a section on line 3—3 of Fig. 2.

Fig. 4 is a detail of the fulcrum.

Fig. 5 is a detail of the suspension link.

Fig. 6 is a detail of the connector.

Fig. 7 is a section on line 7—7 of Fig. 6 with the levers also shown.

Figs 8 and 9 are diagrams showing movements of the several parts.

The usual parts of the car are shown, wherein 1 is the end of the car; 2 the striking casting; 3 the coupler; 4 the coupler lock lifter with its eye 5.

My device comprises a fulcrum 6 secured to the car in any convenient manner, which preferably has a journal portion 7 and a suspension link 8 is mounted upon the fulcrum, or its journal, so as to permit it to swing in a vertical plane only, thus stabilizing the device. The suspension link 8 is provided with a lug 9 which engages a portion 10 of the fulcrum so as to restrict the movement of the suspension link in a vertical plane in either direction. A lever is pivotally connected to the suspension link and operatively connected to the coupler with its opposite ends adjacent the side of the car so that downward movement of the outer end of the lever raises the lock lifter of the coupler. A limited movement is desirable to protect the operator or to support the coupler should its carrier fail.

When the lever comprises a single unit it is connected to the lock lifter 4 of the coupler by a reduced portion 12 which penetrates the eye 5 of the lock lifter in the usual manner and the middle portion is pivotally connected to the suspension link by a horizontal pin penetrating it or in any other convenient

manner, which pivoted connection permits the lever to move or swing sufficiently in a horizontal plane to accommodate the fore and aft movements of the coupler in service.

When the lever is made of two pieces the inner portion or pin lifting lever is connected with the lock lifter 4 of the coupler by a reduced portion 12 which penetrates the lock lifter eye as described above and the outer portion or operating lever extends to adjacent the side of the car, as described above. The inner ends of the operating and pin lifting levers, respectively, are caused to act together in a vertical plane by the connector 13. This connector has an aperture 14 surrounding the pin lifting lever 15 so as to prevent relative movement therebetween in a vertical plane though permitting relative movement therebetween in a horizontal plane, which latter movement is necessary to accommodate the fore and aft movement of the coupler in service. The connector 13 is also provided with another aperture 16 which surrounds the inner end of the operating lever 17 so as to prevent relative movement therebetween in either a horizontal or vertical plane. The connector is pivotally attached to the suspension link 8, preferably by a pivot 18 passing through the fulcrum 6, connector 13 and both levers 15—17. The pin thereby performs the further function of preventing the levers from coming out of the connector.

In the preferred form the fulcrum 6 has a cylindrical portion 7 forming a journal, which portion is smaller than the adjacent part of the fulcrum so as to provide a shoulder 20. The suspension link 8 has a journal bearing which rests upon the journal of the fulcrum, being held therein by the washer 21 and bolt 22.

Figs. 8 and 9 are diagrams to show the movements of the parts. Fig. 8 shows the device in normal position and Fig. 9 shows the device when the outer end of the lever has been moved downwardly to raise its inner end and shows how the suspension link 8 has swung toward the coupler and the levers have pivoted in the connector 13 to permit the inner end of the lever to raise in a vertical line 30 instead of an arcuate line, as it would if the lever were pivotally fulcrumed on the car.

The accompanying drawings illustrate the preferred form of the invention, though it

is to be understood that the invention is not limited to the exact details of construction shown and described, as it is obvious that various modifications thereof within the scope of the claims will occur to persons skilled in the art.

I claim:

1. In an uncoupling device for a car coupler, a fulcrum, a pin lifting lever, an operating lever, a connector operatively connecting said levers, and a suspension link pivotally connected to said fulcrum and pivotally connected to said connector.
2. In an uncoupling device for a car coupler, a fulcrum having a journal, a pin lifting lever, an operating lever, a connector operatively connecting said levers, and a suspension link mounted upon said journal pivotally connected to said fulcrum and pivotally connected to said connector.
3. In an uncoupling device for a car coupler, a fulcrum, a pin lifting lever, an operating lever, a connector operatively connecting said levers, engaging said pin lifting lever so as to prevent relative movement therebetween in a vertical plane though permitting relative movement in a horizontal plane, said connector engaging said operating lever so as to prevent relative movement therebetween in a horizontal or vertical plane, and a suspension link pivotally connected to said fulcrum and pivotally connected to said connector.

4. In an uncoupling device for a car coupler, a fulcrum, a pin lifting lever, an operating lever, a connector operatively connecting said levers having an aperture surrounding said pin lifting lever so as to prevent relative movement therebetween in a vertical plane though permitting relative movement in a horizontal plane, said connector provided with another aperture surrounding said operating lever so as to prevent relative movement therebetween in a horizontal or vertical plane, and a suspension link pivotally connected to said fulcrum and pivotally connected to said connector.

5. In an uncoupling device for a car coupler, a fulcrum, a pin lifting lever, a member engaging said pin lifting lever so as to prevent relative movement therebetween in a vertical plane though permitting relative movement in a horizontal plane, and a suspension link pivotally connected to said fulcrum and pivotally connected to said member, and means for rocking the member and thus operating the pin lifting lever.

6. In an uncoupling device for a car coupler, a fulcrum having a journal, a pin lifting lever, an operating lever, a connector operatively connecting said levers, a suspension link mounted upon said journal, and a pivot pin passing through said fulcrum, connector and levers.

GARTH G. GILPIN.
